(57) **CLAIM**

The ornamental design for a battery device and battery charger assembly, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and right side perspective view of a battery device and battery charger assembly showing our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top plan view thereof, showing the battery device and battery charger assembly in a first state of use;

FIG. 9 is a top plan view thereof, showing the battery device and battery charger assembly in a second state of use;

FIG. 10 is a top plan view thereof, showing the battery device and battery charger assembly in a third state of use;

FIG. 11 is a top plan view thereof, showing the battery device and battery charger assembly in a fourth state of use;

FIG. 12 is a top plan view thereof, showing the battery device and battery charger assembly in a fifth state of use;

FIG. 13 is a top plan view thereof, showing the battery device and battery charger assembly in a sixth state of use;

FIG. 14 is a top plan view thereof, showing the battery device and battery charger assembly in a seventh state of use;

FIG. 15 is a top plan view thereof, showing the battery device and battery charger assembly in an eighth state of use;

FIG. 16 is a top plan view thereof, showing the battery device and battery charger assembly in a ninth state of use;

FIG. 17 is a top plan view thereof, showing the battery device and battery charger assembly in a tenth state of use;

(Continued)

FIG. 18 is a top plan view thereof, showing the battery device and battery charger assembly in an eleventh state of use;

FIG. 19 is a top plan view thereof, showing the battery device and battery charger assembly in a twelfth state of use; FIG. 20 is a top plan view thereof, showing the battery device and battery charger assembly in a thirteenth state of use; and,

FIG. 21 is a top plan view thereof, showing the battery device and battery charger assembly in a fourteenth state of use.

The broken lines in the drawings are for the purpose of illustrating portions of the battery device and battery charger assembly that form no part of the claimed design.
